IRRIGATING IMPLEMENT FOR PLANTS OR THE LIKE

James R. Moore, Jr., and Charles I. Bell, Jr.,
Greenwood, Miss.

Application February 11, 1955, Serial No. 34,491

Term of patent 14 years

(Cl. D35—2)

Fig. 1 is an elevational view of the irrigating implement for plants or the like showing our new design; .

Fig. 2 is a top plan view of our new irrigating implement for plants or the like; .

Fig. 3 is a bottom plan view thereof; and

Fig. 4 is an enlarged portion of Fig. 1 showing a section cut away.

We claim:

The ornamental design for an irrigating implement for plants or the like, as shown.
